(57) **CLAIM**

The ornamental design for a heat pump water heater as shown and described.

DESCRIPTION

FIG. 1 is a front perspective view of a heat pump water heater showing our new design and with the heat pump housing covered omitted for clarity of illustration.

FIG. 2 is a front view thereof with certain components omitted for clarity of illustration.

FIG. 3 is a rear view thereof with certain components omitted for clarity of illustration.

FIG. 4 is a left view thereof with certain components omitted for clarity of illustration.

FIG. 5 is a right view thereof with certain components omitted for clarity of illustration.

FIG. 6 is a top view thereof with certain components omitted for clarity of illustration; and,

FIG. 7 is an exploded view thereof.

Any broken lines shown represent unclaimed subject matter and form no part of the claimed design. Any shade lines shown represent surface shading and not surface ornamentation, color, or material type.

1 Claim, 7 Drawing Sheets
